UNITED STATES PATENT OFFICE

153,111

DESIGN FOR A SAFETY RAZOR

Henry D. Bratter, Washington, D. C.

Application July 8, 1948, Serial No. 147,442

Term of patent 14 years

(Cl. D22—3)

To all whom it may concern:

Be it known that I, Henry D. Bratter, a citizen of the United States, residing in the city of Washington, District of Columbia, have invented a new, original, and ornamental Design for a Safety Razor, of which the following is a specification, reference being had to the accompanying drawing, forming part thereof.

Figure 1 is a perspective view of a safety razor, showing my new design;

Figure 2 is a side elevational view;

Figure 3 is a top plan view; and

Figure 4 is an end view thereof.

The characteristic features of my design reside in the portions shown by means of full lines in the drawing.

I claim:

The ornamental design for a safety razor, as shown and described.

HENRY D. BRATTER.
